DESIGN FOR A PHOTOGRAPHIC MOUNT OR ARTICLE OF SIMILAR NATURE

George W. Higgins, Columbus, Ohio

Application April 14, 1944, Serial No. 113,247

Term of patent 3½ years

(Cl. D29—20)

To all whom it may concern:

Be it known that I, George W. Higgins, a citizen of the United States of America and a resident of Columbus, in the county of Franklin and State of Ohio, have invented a new, original, and ornamental Design for a Photographic Mount or Article of Similar Nature, of which the following is the specification, reference being had to the accompanying drawing, forming a part thereof:

photographic mount or article of similar nature showing my new design.

I claim:

The ornamental design for a photographic mount or article of similar nature, substantially as shown.

GEORGE W. HIGGINS.
